UNITED STATES PATENT OFFICE.

ARTHUR BATES, FRED RICKS, AND ALBERT AMOS ASTON, OF LEICESTER, ENGLAND,
ASSIGNORS TO UNITED SHOE MACHINERY CORPORATION, OF PATERSON, NEW JER-
SEY, A CORPORATION OF NEW JERSEY.

CUTTER ADJUSTMENT.

Application filed February 2, 1921. Serial No. 441,849.

To all whom it may concern:

Be it known that we, ARTHUR BATES, FRED RICKS, and ALBERT A. ASTON, subjects of the King of England, and residents of Leices-
ter, Leicestershire, England, have invented
certain Improvements in Cutter Adjust-
ments, of which the following description,
in connection with the accompanying draw-
ings, is a specification, like reference char-
acters on the drawings indicating like parts
in the several figures.

This invention relates to fastening in-
serting machines and to the severing of fas-
tenings from strips of material supplied
thereto. More particularly the invention re-
lates to machines for inserting metallic fas-
tenings such as are used in the manufacture
of boots and shoes and to the adjustment
of cutters commonly used in certain of such
machines for severing from strips of ma-
terial metallic fastenings to be inserted in
shoes.

The invention is described in the accom-
panying specification with reference to the
adjustment of the cutters of a type of fas-
tening inserting machine commonly known
as the taper nail tacking machine in which
a strip of sheet metal of a width equal sub-
stantially to the length of the fastenings
30 to be inserted is fed to cutters with which
the machine is provided, so that fastenings
to be driven by the machine may be cut
from the strip. A machine of this type is
illustrated and described in United States
35 Letters Patent No. 490,625, granted Jan. 24,
1893, on an application filed in the name of
Louis Goddu to which reference may be
had for a fuller description thereof.

The cutters of machines of this type are
commonly held in a pair of relatively mov-
able cutter holders. In the illustrated ma-
chine, as in that of the disclosure of the
patent referred to, one of these cutter
holders is stationary and the other is mov-
able to bring the two cutters into cutting
relation, the strip of fastening material be-
ing fed forward step by step to provide the
material of which the fastenings are formed.

It is needful from time to time to remove

the cutters from the machine for the pur- 50
pose of grinding them as they become worn
or their cutting edges otherwise damaged.
It is necessary when replacing the cutters
to position them in their holders with a very
considerable degree of accuracy, otherwise 55
the machine will fail to cut fastenings hav-
ing the desired smoothness and uniform
shape. If the cutters are improperly ad-
justed, the fastenings may have burrs and
ragged portions, appearing as if torn in- 60
stead of smoothly cut from the strip.

Heretofore the replacement and adjust-
ment of the cutters in such machines have
called for a series of operations requiring
careful attention and skill and consuming 65
a substantial amount of time. Thus in re-
placing the cutters of machines of the
type set forth in said Letters Patent, it is
necessary (1) to place the main shaft of
the machine in a definite position in which 70
a cam operating a cutter controlling lever
has advanced the lever to its limit of cut-
ting movement; (2) to remove the fasten-
ing driver from its clamp in the driver bar;
(3) to thread the driver through a hori- 75
zontal passage in the nail guiding throat; (4)
to move the fixed cutter forwardly in its
holder until its vertical edge contacts with
the driver thus threaded in the path of the
cutter in its holder and then to clamp the 80
cutter in its holder, its vertical edge then
being in a position substantially to the
right, viewing the machine from the opera-
tive's position, of the path of the driver
when in operation; (5) to reinser the driver 85
in its clamping and driving bar; and (6)
to move the movable cutter forward in its
holder until its vertical edge contacts with
the driver and then clamp it in its holder. 90

It is an object of the present invention to
simplify the procedure of inserting and ad-
justing cutters such as those of machines of
the type above referred to so as to reduce
the necessity for skill in its performance
and so as to reduce the time consumed. 95

A feature of the invention consists in the
provision of means for bringing the cutter
holders into the relative position which they

should occupy at the conclusion of each cutting operation without turning over the machine as a whole, and this quickly and positively and entirely independent of the 5 position in which the different parts of the machine may have stopped.

A further feature of the invention consists in the provision of a stop arranged to indicate the position which the cutting edge 10 of a cutter should normally occupy at the conclusion of each cutting operation. In the illustrated machine, a pair of stops in the form of shoulders are provided, one arranged to contact with the cutting edge of 15 each cutter when the cutters are properly adjusted in the cutter holders and the cutter holders are in the relative position they occupy at the conclusion of each cutting operation, so that by bringing the cutting 20 edges of the cutters against these stops while the cutter holders are in the position they occupy at the conclusion of each cutting operation and then clamping the cutters in the holders they may be readily and accurately 25 replaced without the necessity of the comparatively lengthy procedure outlined above.

Machines of this character are often provided with at least one cutter holder which 30 is rocked about an axis at right angles to the plane of the cutting movement. In assembling these machines, either originally or after they have been dismantled, it is necessary that the plane of movement of the 35 cutter held in this movable cutter holder be accurately adjusted with respect to the position of the other cutter. This has ordinarily been done in the past by packing or shimming up the cutter in its holder with 40 strips of paper or other sheet material, or by a more or less laborious filing of the different parts to bring the cutters into proper relation.

It is a further object of the present invention 45 to provide means for positively adjusting one of the cutters of such machines so as to bring the plane of cutting movement of that cutter into proper relation to the cutting edge of the other cutter. In the 50 illustrated machine this is accomplished by forming the pivot or journal of the movable cutter holder in two parts relatively adjustable axially or lengthwise of the pivot so that the plane of the cutter holder may be 55 adjusted lengthwise of its pivot and so that the cutter holder may be locked in its adjusted position.

With the above and other objects in view, 60 the invention will now be described in connection with the accompanying drawings, which show an illustrative embodiment thereof, and pointed out in the claims. It should be understood, however, that this disclosure is primarily for the purpose of illustration 65 and that the invention is in no way limited

to the form of machine shown but may be embodied in machines of other types within the scope of the subjoined claims.

In the drawings,

Fig. 1 illustrates a front view of the cutters and cutter operating means and associated parts of a fastening inserting machine;

Fig. 2 is a cross section on line 2—2 of Fig. 1;

Fig. 3 is a side view, partly in section, 75 showing an adjustable pivot or journal for the movable cutter holder of the machine of Fig. 1;

Fig. 4 is a rear elevation on a larger scale than Fig. 1 of the throat piece of the machine;

Fig. 5 is a cross section on the line 5—5 of Fig. 4, showing also the relation of the cutters to the throat piece and to the cutter adjusting stops of the machine;

Figs. 6 and 7 are an elevation and bottom view respectively of a stop bearing bushing inserted in the throat piece of the machine to facilitate the adjusting of the movable cutter.

The illustrated machine is provided with a main drive shaft 10 journaled in suitable bearings and carrying a cutter operating cam 12 provided with a rise 14. Engaging the cam 12 and normally held in contact therewith by a compression spring 16 is a roll 18 mounted near one end of a movable cutter carrying lever 20, this lever being pivoted to the frame 22 of the machine, as will be more fully hereinafter described, at 100 24. Carried by the lever 20 and removably attached thereto as by screws 26 is a movable cutter holder 28 in which is carried the movable cutter 30. Clamped to a fixed portion of the frame of the machine, as by a screw 32, is the fixed cutter holder 34 by which is carried the fixed cutter 36. Cutter 30 has its cutting edge radial of the path of movement of lever 20 and cutter holder 28, so that the two cutters act as shears in severing fastenings from a strip or ribbon of fastening material. A throat piece 38 provided with a nozzle 40 and formed with a fastening receiving and directing opening 42 is removably attached to the fixed cutter holder as by screws 44.

The machine is provided with a driver bar 46 to which is clamped in any appropriate manner a driver 48 arranged for reciprocation through the opening in the throat piece and nozzle in timed relation to the operation of the cutters to insert in the work fasteners severed by the cutters from a strip of fastening material appropriately fed thereto.

A set screw 50 may be provided, threaded into an appropriate rigid part of the frame of the machine and adjustable to engage the rear end of the fixed cutter to assist in maintaining it in adjusted position.

The portions of the machine so far described may be substantially in accordance with the showing of United States Letters Patent No. 490,625, above referred to, 5 and to which reference may be had for a disclosure of appropriate mechanism for operating the moving parts thereof.

To facilitate the adjustment of the cutters of the machine, a cam lever 52, provided with 10 a cam portion 54 and a handle 56, is pivoted at 58 to a rigid part of the frame of the machine, the cam portion of the lever being so formed that when the lever is swung in a counter clockwise direction from the position 15 which it occupies in Fig. 1 it will move lever 20 to the position which it occupies at the conclusion of each cutting operation, and this irrespective of the position of cam 12. In other words, cam 54 is of such a form that 20 it moves lever 20 to the same position to which it is moved by the highest portion of the rise 14 of cam 12. Lever 20 may conveniently be provided with a roll 60 to cooperate with the cam portion 54 of lever 52.

25 Lever 20 is provided with a stop secured thereto in any suitable manner and illustrated as a shoulder 62 so located that, when lever 20 is moved to cutter adjusting position under the influence of lever 52, shoulder 62 will be in such position that engagement 30 of the cutting edge of the fixed cutter 36 therewith will bring that cutter into its proper position. Similarly the throat piece 38, which is rigidly connected to the fixed 35 cutter holder, is provided with a stop which, when engaged by the cutting edge of the movable cutter, with the lever 20 in the position which it occupies at the conclusion of each cutting movement and to which it 40 may readily be moved by lever 52, ensures the correct positioning of the movable cutter. As illustrated this stop consists of a surface formed as a shoulder 64 of a bushing 36 seated in an enlarged opening 68 in the 45 upper portion of the throat piece and provided with a central opening 70 in alignment with the opening 42 of the throat and nozzle. Conveniently this bushing may also be provided with a surface 72 for engagement with 50 the fixed knife to ensure its correct position circumferentially of the throat opening. As shown, these surfaces are formed by removing a portion of the periphery of the bushing at the lower end thereof.

55 For the purpose of adjusting the movable cutter along its axis of rotation, the pivot or journal 24 of the lever 20 is formed in two relatively longitudinally adjustable parts 80 and 82 having threaded connection at 84 for purposes of adjustment and provided with lock nuts 86 by which they may be positively retained in adjusted relation. The pivot or journal 24 may conveniently be of conical form and is shown as provided 60 with a threaded portion 88 for engagement

with nuts 90 for holding it in the desired relation to its bearing in the frame of the machine.

To bring the plane of the cutting arm of the movable cutter into correct relation with 70 the cutting edge of the movable cutter into correct relation with the cutting edge of the fixed cutter when assembling the machine, it is necessary only to adjust the nuts 90 so as to bring and hold the portion 80 of 75 the pivot in proper position in its bearing and then to adjust the portion 82 of the pivot to bring the movable cutter into the correct plane, locking it in that position by means of nuts 86.

In replacing the cutters after their removal for grinding or for other purposes, it is only necessary to raise the lever 52 so as to throw lever 20 into the position which it occupies at the conclusion of each cutting 80 operation, then to position the fixed cutter 36 with its cutting edge against shoulder 62 and the movable cutter 30 with its cutting edge against shoulder 64 carried by the bushing of the throat member, clamping 85 them in these positions by means of screws 32 and 26, then bringing screw 50 into position to bear against the rear end of the fixed cutter. The cutters are then in correct operative relation and the machine may be started forthwith.

Having described our invention, what we claim as new and desire to secure by Letters Patent of the United States is:—

1. A machine for inserting metallic fastenings having, in combination, a pair of cutters for severing fastenings from a strip of fastening material, and a stop supported rigidly with respect to one of the cutters and arranged to engage the cutting edge of 100 the other cutter when that cutter is in the position it should occupy at the conclusion of each cutting operation.

2. A machine for inserting metallic fastenings having, in combination, a pair of cutters for severing fastenings from a strip of fastening material, a driver arranged to insert the severed fastenings, and a stop rigidly supported with respect to each cutter arranged to engage the other cutter 105 when that cutter is in the position it should occupy at the conclusion of each cutting operation.

3. A machine for inserting metallic fastenings having, in combination, a pair of cutters, a pair of cutter holders arranged to hold said cutters, and a stop carried by one of said cutter holders in position to engage the cutter carried by the other cutter holder when that cutter is in the position it 120 should occupy at the conclusion of each cutting operation.

4. A machine for inserting metallic fastenings having, in combination, a pair of cutters, a pair of cutter holders arranged to 125

- hold said cutters, and a throat piece carried by one of said cutter holders and provided with a bushing having a portion of its periphery removed to form a stop in position to engage the cutter carried by the other cutter holder when that cutter is in the position it should occupy at the conclusion of each cutting operation.
5. A machine for inserting metallic fastenings having, in combination, a throat piece, a driver movable through the opening therein, a cutter, and a bushing having an opening in alignment with the opening of the throat piece and provided with a surface into contact with which the cutter may be brought for adjustment thereof.
6. A machine for inserting metallic fastenings having, in combination, a cutter for severing a fastening from a strip of fastening material, a driver for inserting the fastening in the work, and a stop positioned to engage the cutter to indicate the position it should occupy at the conclusion of each cutting operation.
7. A machine for inserting metallic fastenings having, in combination, a pair of relatively movable cutter holders and a cutter adjustably mounted in each cutter holder, each cutter holder being provided with a stop stationary with respect thereto, each stop being arranged to be engaged by the cutter carried by the other cutter holder correctly to position the cutters.
8. A machine for inserting metallic fastenings having, in combination, a pair of relatively movable cutter holders, a cutter adjustably clamped to each cutter holder, each cutter holder being provided with a shoulder stationary with respect thereto, and each shoulder being arranged at the end of the path of relative movement of the cutter carried by the other cutter holder to facilitate the adjusting of the cutters.
9. A throat piece for machines for inserting metallic fastenings having a driver receiving bushing stationary relatively thereto and partially cut away so as to provide a shoulder adjacent to the driver receiving openings of the throat and of the bushing.
10. A machine of the class described having a throat member, a cutter, and a bushing for the throat member having a portion of the periphery thereof removed to provide an engaging surface for said cutter.
11. A bushing for the throat of a metallic fastening inserting machine having a portion of the periphery thereof removed to provide a pair of plane surfaces arranged at an angle to one another for engagement with the cutters of the machine.
12. A machine for inserting metallic fastenings having, in combination, a movable cutter holder, a cutter therein, means for moving said cutter holder in a path of which the cutting edge of the cutter is a radius to shear a fastening from a strip of fastening forming material, and means separate from said cutter moving means and operable independently thereof to move said cutter holder into the position which it should normally occupy at the conclusion of each cutting operation.
13. A machine for inserting metallic fastenings having, in combination, a lever, a cutter holder carried thereby, a cutter adjustably carried by the cutter holder, a cam for rocking said lever to shear a fastening from a strip of fastening forming material, the shearing edge of the cutter being radial of the path of rocking movement of the lever and the cutter holder and means separate from said cam and operable independent of the position thereof to move said lever and the cutter holder carried thereby into the position which they should normally occupy at the conclusion of each cutting operation.
14. A machine for inserting metallic fastenings having, in combination, a lever, a cutter holder carried thereby, a cutter adjustably carried by said cutter holder, means for rocking said lever to cause said cutter to cut a fastening from a strip of fastening forming material, and a cam member operable to move said lever and the cutter holder carried thereby into the position which they normally occupy at the conclusion of each cutting operation independently of the condition of said lever rocking means.
15. A machine for inserting metallic fastenings having, in combination, a lever, a cutter holder carried thereby, a cutter adjustably mounted in said cutter holder, a cam for rocking said lever to cause said cutter to cut a fastening from a strip of fastening forming material, and a cam separate from said first-named cam and operable to move said lever and the cutter holder carried thereby into the position which they should normally occupy at the conclusion of each cutting operation independently of the position of said first-named cam.
16. A machine for inserting metallic fastenings having, in combination, a stationary cutter, a lever, a movable cutter holder carried thereby, a cutter adjustably carried by said cutter holder, means for rocking said lever to cause said cutters to cut a fastening from a strip of fastening forming material, and a cam member arranged to move said lever and said movable cutter into the position which they should normally occupy at the conclusion of each cutting operation independently of the condition of said lever rocking means.
17. A machine for inserting metallic fastenings having, in combination, a lever, a cutter holder carried thereby, a cutter adjustably clamped in said cutter holder, a cam for rocking said lever to cause said cutter to cut a fastening from a strip of fasten-

- ing forming material, and a cam operable to move said lever and the cutter holder carried thereby into the position which they should normally occupy at the conclusion of each cutting operation independently of the position of said first named cam.
18. A metallic fastening inserting machine having, in combination, a driver, a cam, a cutter arranged to sever fastenings from a strip of fastening forming material and present them in position to be inserted by said driver, a cutter actuating lever operated by said cam, a spring tending to hold the lever to the cam, and a setting device operable to hold the lever away from the cam in a position appropriate for cutter adjusting.
19. A metallic fastening inserting machine having, in combination, a driver, a cam, a cutter arranged to sever fastenings from a strip of fastening forming material and present them in position to be inserted by said driver, a cutter actuating lever operated by said cam, a spring tending to hold the lever to the cam, and a setting device for holding the lever away from the cam against the tension of said spring in the position it should normally occupy at the conclusion of each cutting operation.
20. A machine for inserting metallic fastenings having, in combination, a cutter carrier, a cutter carried thereby, a conical pivot member adjustably connected to said cutter carrier, a bearing therefor, and means for locking said cutter carrier in adjusted relation to said conical pivot member adjustable to compensate for imperfections in the conical pivot member or its bearing.
21. In a machine for inserting metallic fastenings, a cutter carrier, a conical pivot member, and means for locking the cutter carrier in adjusted position axially of said pivot member.
22. In a machine of the class described, a lever, a conical journal adjustably connected to said lever, a conical bearing for said journal, and means for locking the lever in adjusted position lengthwise of said journal.
23. In a machine for inserting metallic fastenings, a cutter carrier, a cutter rigidly carried thereby, a pivot for the cutter carrier, and means for holding the cutter carrier in adjusted position axially of said pivot.
24. A machine for inserting metallic fastenings having, in combination, a cutter carrier, a cutter carried thereby, and a conical pivot member adjustably locked to said cutter carrier, and constituting a support therefor.
25. A machine for inserting metallic fastenings having, in combination, a fixed cutter holder and a movable cutter holder, a cutter carried by each holder, means for moving said movable holder back and forth to cause the cutter carried thereby to cut fastenings from a strip of fastening forming material, and means separate from said first-named means for moving said movable cutter holder into the position which it should normally occupy at the conclusion of each cutting operation independently of the condition of said first-named means.
26. A metallic fastening inserting machine having, in combination, a driver, a movable cutter holder, a cutter carried thereby, means for moving said cutter holder to cause said cutter to cut fastenings from a strip of fastening forming material and present them in position to be inserted by said driver, and means for positioning said cutter holder in the position which it should normally occupy at the conclusion of each cutting operation independently of the position of the driver.
27. A machine for inserting metallic fastenings having, in combination, a fixed cutter holder and a movable cutter holder, a cutter carried by each holder, a cam for moving said movable holder back and forth to cause the cutter carried thereby to cut fastenings from a strip of fastening forming material, and a manually shiftable cam, separate from said first-named cam, for moving said movable cutter holder into the position which it should normally occupy at the conclusion of each cutting operation independently of the position of said first-named cam.
28. A metallic fastening inserting machine having, in combination, a driver, a movable cutter holder, a cutter carried thereby, a cam for moving said cutter holder to cause said cutter to cut fastenings from a strip of fastening forming material and present them in position to be inserted by said driver, and a manually operable cam for positioning said cutter holder in the position which it should normally occupy at the conclusion of each cutting operation independently of the position of the driver.
29. A machine for inserting metallic fastenings having, in combination, a cutter holder, a cutter carried thereby, means for moving said cutter holder back and forth to cause said cutter to cut fastenings from a strip of fastening forming material, means independent of said first-named means for moving said cutter holder into the position which it normally occupies at the conclusion of each cutting operation, a conical pivot member adjustably connected to said cutter holder, and means for locking said pivot member to said cutter holder adjustable to compensate for imperfections in the pivot member or its bearing.
30. A machine for inserting metallic fastenings having, in combination, a cutter holder, a cutter carried thereby, a cam for

moving said cutter holder back and forth to cause said cutter to cut fastenings from a strip of fastening forming material, means independent of said first-named means for 5 moving said cutter holder into the position which it should normally occupy at the conclusion of each cutting operation, a pivot member adjustably connected to said cutter holder, and means for locking said pivot

member to said cutter holder adjustable axially of said pivot member to compensate for imperfections in the pivot member or its bearing. 10

In testimony whereof we have signed our names to this specification.

Certificate of Correction.

Patent No. 1,582,959.

ARTHUR BATES ET AL.

Granted May 4, 1926, to

It is hereby certified that error appears in the printed specification of the above-numbered patent requiring correction as follows: Page 3, lines 71 and 72, strike out the words "of the movable cutter into correct relation with the cutting edge"; and that the said Letters Patent should be read with this correction therein that the same may conform to the record of the case in the Patent Office.

Signed and sealed this 11th day of October, A. D. 1927.

[SEAL.]

M. J. MOORE,
Acting Commissioner of Patents.
